UNITED STATES PATENT OFFICE.

EDWARD LAPOINT, OF GLENS FALLS, NEW YORK.

CALIPERS.

1,262,678.

Specification of Letters Patent. Patented Apr. 16, 1918.

Application filed June 8, 1917. Serial No. 173,662.

To all whom it may concern:

Be it known that I, EDWARD LAPOINT, a citizen of the United States, residing at Glens Falls, in the county of Warren, State 5 of New York, have invented certain new and useful Improvements in Calipers; and I do hereby declare the following to be a full, clear, and exact description of the invention, such as will enable others skilled 10 in the art to which it appertains to make and use the same.

This invention relates to improvements in calipers and has for an object to provide as an article of manufacture a caliper which 15 may be constructed in novel manner entirely from sheet metal and may thus be manufactured and marketed at a relatively low cost.

With the above and other objects of similar nature in view, the invention consists 20 in the construction, combination and arrangement of parts, set forth in and falling within the scope of the appended claim.

In the drawing:—

25 Fig. 1 is a perspective view of a caliper constructed in accordance with the invention.

Fig. 2 is a longitudinal section therethrough,

30 Fig. 3 is a transverse section taken on the line 3—3 of Fig. 2, and

Fig. 4 is a plan view of the blank from which one of the members of the caliper is formed.

35 Referring now more particularly to the accompanying drawing, the caliper consists of two members 5 and 6 respectively which are superimposed one upon the other and are connected for longitudinal sliding movement. Each of the members 5 and 6 is stamped in blank from sheet metal such as steel, galvanized tin or the like and of a gage to provide the requisite stiffness. The member 5 consists of an elongated strip 40 7 having therein a longitudinal slot 8 and further provided at one end with an enlarged handle portion 9.

45 At the opposite end of the strip 7 there is formed an integral lateral extension 10 which is bent on the fold line 11 as indicated in dotted lines Fig. 4 to lie in a plane at right angles to the plane of the strip. The member 6 of the caliper also comprises an elongated strip as is indicated at 12 ad-

jacent one end of which there is provided 55 an aperture 13 which registers with the slot 8 in the member 5 to receive therethrough a screw 14 which passes loosely through the slot and has engaged thereon a wing-nut 15.

The members 5 and 6 are in this manner 60 connected for longitudinal sliding adjustment, the nut 15 being tightened upon the screw to hold the members in adjusted position. The member 6 is likewise provided at its outer end with a lateral extension 16 65 similar to the extension 10 and bent as is the latter to lie in a plane at right angles to the strip 12. The extensions 10 and 16 thus provide suitable coöperating gage elements between which articles or material to 70 be measured are interposed, and are movable toward and away from each other by reason of the adjustment above described.

The strip 12 of the member 6 has designated on its upper face a suitable scale 17 75 for indicating the distance between the gage elements 10 and 16. In order to maintain the members 5 and 6 in longitudinal alignment, there are formed on the side of the strip 7 integral fingers 18 which are bent 80 to embrace the strip 12 and serve to guide the latter in its movement.

What I claim is:—

85 A caliper consisting of a pair of slidably connected members, each formed from a sheet metal blank and being provided at corresponding ends with lateral extensions bent to extend at right angles to the faces of said members and constituting coöperating gage elements, one of said members being provided at its other end with a handle and between said handle and its gage element being longitudinally slotted and being further provided on opposite side edges with integral guide fingers bent to slidably embrace the other member, said other member having delineated thereon a scale and having an aperture therein registering with the slot in the first mentioned member, and adjusting means passed through said registering aperture and slot.

95 In testimony whereof, I affix my signature in the presence of two witnesses.

EDWARD LAPOINT.
